UNITED STATES PATENT OFFICE.

WILHELM PETZOLD, OF LEIPSIC, ASSIGNOR TO JOHANN WILHELM WOHLERS,
OF HAMBURG, GERMANY.

CIGAR-CUTTER.

SPECIFICATION forming part of Letters Patent No. 242,690, dated June 7, 1881.

Application filed April 14, 1881. (No model.)

To all whom it may concern:

Be it known that I, WILHELM PETZOLD, of Leipsic, in the Empire of Germany, have invented a certain new and Improved Cigar-Cutter, of which the following is a specification.

The object of my invention is to provide a very desirable utensil for cutting out a V-shaped piece from the tip of a cigar and forming therein a groove or notch of corresponding shape, thereby increasing the cut surface through which the smoke may be drawn.

The invention consists in the combination of a stock or handle having a funnel-shaped opening in its end for the insertion of a cigar, a lever carrying an angular or V-shaped knife pivoted in the opposite end of said handle or stock, a spring for throwing the lever outward, and a spring-catch for engaging with said lever and holding it in its closed position, as fully hereinafter described.

In the accompanying drawings, Figure 1 is a side view of my improved cutter. Fig. 2 is a section thereof in a plane parallel with the plane of movement of said lever. Fig. 3 represents a section at right angles thereto. Fig. 4 represents a transverse section on the dotted line xx , Fig. 2. Fig. 5 represents an end view, and Fig. 6 represents a cigar having its tip cut by my improved cutter.

Similar letters of reference designate corresponding parts in all the figures.

A designates the shell handle or stock of the cutter. This shell or stock may be made similar to the handle of a pocket-knife, but at one end it carries a funnel-like guide, a , for receiving the point of the cigar. This funnel is very clearly shown in Fig. 3. To the other end of shell A is pivoted a lever, B, which fits between the walls or sides of the handle or

stock, and carries a V-shaped knife, C, at the end adjacent to the funnel a , as clearly shown. The said knife works transversely to the funnel a , and the lower edge of the funnel is made of similar shape to the knife, so that 45 the knife will work close to the funnel. A suitable spring, m , is employed to throw the lever B up or outward in the direction away from under the funnel, but it is arrested by the end of the knife engaging with the top rim 50 of funnel a , as will be understood by reference to Fig. 2.

The end of the cigar is inserted into the funnel a when the knife is up, as in Figs. 1 and 2, and then the knife is forced down to detach 55 the point of the cigar from the body thereof, and at the same time cut a V-shaped groove into the body of the cigar, as is illustrated at b , Fig. 6. After the knife is pressed down it is arrested in this closed position by a spring- 60 catch, r , placed inside of the shell. The point of the catch enters a hole or recess, s , in the handle or stock B. For opening the knife again a pressure is exerted on pin d , which is fastened at one end to spring-catch r and 65 projects through the opposite side of the body. When the pin d is pressed inward the catch r is disengaged from the hole s and the lever is thrown out by the spring m .

What I claim, and desire to secure by Letters Patent, is—

A cigar-cutter constructed of the handle A, lever B, and V-shaped knife C, said handle being provided with a funnel, a , catch r , and stop-pin d , substantially as herein shown and 75 described.

WILHELM PETZOLD.
